UNITED STATES PATENT OFFICE.

ARTHUR J. M. RECKLIN, OF BAY CITY, MICHIGAN.

KITE.

1,067,272.

Specification of Letters Patent.

Patented July 15, 1913.

Application filed July 1, 1912. Serial No. 706,971.

To all whom it may concern:

Be it known that I, ARTHUR J. M. RECKLIN, a citizen of the United States of America, residing at Bay City, in the county of 5 Bay and State of Michigan, have invented certain new and useful Improvements in Kites; and I do hereby declare the following to be a full, clear, and exact description of the invention, such as will enable others 10 skilled in the art to which it appertains to make and use the same.

My invention relates to improvements in kites, and its object is to provide a knock down kite that can be easily and quickly 15 assembled for use, or disassembled and packed in close relation for storage or transportation, and to provide the same with various new and useful features hereinafter more fully described and particularly 20 pointed out in the claims.

My device consists essentially of a detachable main plane; a tail frame detachably secured thereto; braces pivoted to the frame of the main plane detachably secured 25 to each other and to the tail frame and foldable against the frame of the main frame; and horizontal and vertical rudders detachably secured to the tail frame, as will more fully appear by reference to the accompanying drawings, in which:

Figure 1 is a plan view of a device embodying my invention; Fig. 2 a front view of the same; Fig. 3 a side view of the same; Fig. 4 an enlarged detail of the braces and 35 front end of the tail frame; Fig. 5 an enlarged detail of the clips for securing the rudders to the tail frame; Fig. 6 a front elevation of the device when disassembled and arranged for storage or transportation; 40 and Fig. 7 a detail of the tail frame.

Like numbers refer to like parts in all of the figures.

1 represents the main plane of the device preferably comprising a rectangular frame 45 covered by suitable material such as canvas or paper as at 2.

3 represent braces hinged to the frame as at 4 and adapted to fold outward close to the same.

5 is a straight rod forming the lower 50 member of the tail frame. 6 the upper member of the tail frame spaced apart from the lower member at the front end by cross bars 8, and at its rear end curved down and 55 thence parallel with the bar 5 and in con-

tact therewith, being secured thereto by a suitable lashing 7 wound around the same.

9 is a horizontal rudder fixed on the rod 5 near the rear end of the tail frame by means of clips 10 and a thumb screw 11. 60

12 is a vertical rudder secured to the rear end of the rod 5 by means of clips 10 and thumb screw 11.

13 is a hook and 14 an eye by which the 65 ends of the braces are detachably secured to each other when in use.

Projecting oppositely from the said frame and opposite the cross bars 8 are pins 15 which detachably engage the adjacent ends of the braces 3 below, and the middle of the 70 frame of the plane 1 above, and thus connect the same and hold the tail frame properly positioned vertically, and at right angles to said plane.

The tail frame and both rudders are provided 75 with paper or canvas covers 2 or other suitable material the same as the main plane of the device.

The operation of my invention will be readily understood from the foregoing description. By loosening the thumb screws 80 11 the rudders can be quickly removed from the tail frame and by detaching the hook and eye 13 and 14 the tail frame is in like manner easily detached from the frame of 85 the plane 1. The parts can then be readily arranged as shown in Fig. 6 whereby they will be in compact form suitably arranged for transportation or storage, and can again be quickly reassembled for use as occasion 90 may require.

In flying this kite the string or cord may be readily attached thereto in any convenient manner preferably to the front end of the tail frame and properly adjustable 95 vertically thereon, this being obvious the string is not shown in the drawings.

What I claim is:—

1. A kite, comprising a main plane having a frame, a tail frame comprising a 100 straight lower rod and an upper rod spaced apart therefrom at its forward end by vertical bars and curved at its rear end to engage the lower rod and attached thereto, a horizontal rudder and a vertical rudder detachably secured to the tail frame, and means for detachably securing the tail frame to the frame of the main plane. 105

2. A kite, comprising a rectangular main plane provided with a suitable cover, a tail 110

frame comprising two rods spaced apart at the front by two vertical bars one of said rods being bent at the rear of said bars toward the other rod and attached thereto, a 5 vertical rudder and a horizontal rudder detachably secured to one of said rods, braces hinged to the main plane and engaging the tail frame to hold the same perpendicular to the main plane, and means for attaching 10 the tail frame to the braces and to the main plane.

3. A kite, comprising a rectangular main frame, a tail frame consisting of a straight lower rod, an upper rod spaced apart from 15 the lower rod at the front, vertical bars between rods near the front, the upper rod being bent downward and rearward and attached to the lower rod one of said rods also being prolonged rearward to receive the 20 rudders, braces pivotally attached to the main frame at one end, means for attaching the braces to each other at the free end, pins oppositely projecting from the tail frame to engage the braces and main plane,

a horizontal rudder and a vertical rudder 25 each having clips thereon to receive the extended rod of the tail frame, and set screws to secure the rudders on the rod.

4. A kite, comprising a rectangular main plane, a tail frame having one long straight 30 lower rod and a shorter bent upper rod secured to the lower rod at the rear end and spaced apart therefrom at the front end, vertical bars between the rods and beneath 35 the main plane, braces hinged to the main plane at one end and provided with detachable fastenings at the other end, pins in the tail frame to engage the main plane and the braces, a horizontal rudder and a vertical rudder each provided with clips to receive the lower rod of the tail frame and set screws to retain the rudders on the rod. 40

In testimony whereof I affix my signature in presence of two witnesses.

ARTHUR J. M. RECKLIN.
